UNITED STATES PATENT OFFICE.

CLARENCE M. FIELDS AND WALTER WORRICK, OF BELLEFONTAINE, OHIO.

MUSICAL INSTRUMENT.

Application filed January 31, 1925. Serial No. 6,095.

To all whom it may concern:

Be it known that we, CLARENCE M. FIELDS and WALTER WORRICK, citizens of the United States, residing at Bellefontaine, in the county of Logan and State of Ohio, have invented new and useful Improvements in Musical Instruments, of which the following is a specification.

This invention relates to a device for producing musical sounds, the general object of the invention being to provide a strip of steel with means for supporting the same in such a manner that when struck with a hammer or the like the strip will give off musical sounds.

Another object of the invention is to so form the supporting means that the device can be held in the lap with one hand adjusting the steel strip and the other using the hammer.

This invention also consists in certain other features of construction and in the combination and arrangement of the several parts, to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:—

Figure 1 is a view showing how the device is used.

Figure 2 is a bottom plan view of the device.

Figure 3 is a top plan view.

In these views, 1 indicates a tapered strip of tempered steel which has its large end clamped between the two halves of a base 2, this base being of cylindrical form with enlarged ends. The end of the strip which is held by the base is bent so that the strip extends upwardly at an angle from the base. Supporting members 3 and 4, each formed of a wire frame with its ends passing through the base and held in position by nuts 5, serve to hold the device in the lap of the user, as shown in Figure 1. The member 3 has its major part flat and its outer end curved, as at 6, so that it will extend across

the lap and engage one of the legs of the user while the member 4 curves downwardly to engage the other leg. Bolts 7 hold the two parts of the base in clamping position 55 on the strip and the ends of the frames 3 and 4 with the bolts thereon also act to hold the two parts of the base together.

As shown in Figure 1, the device is placed on the lap of the user and is held thereon by the curved parts of the frames 3 and 4 engaging the legs of the user. The blade or strip 1 extends upwardly and its small end is adapted to be grasped by one hand of the user while the other hand holds the hammer 8 or other device for striking the strip. The strip is adjusted by the left hand so as to produce the different musical notes as it is struck by the hammer. 60

We prefer to call this device a musical 70 "buck" and it is designed to take the place of the saw blade now used for producing musical sounds.

It is thought from the foregoing description that the advantages and novel features 75 of the invention will be readily apparent.

We desire it to be understood that we may make changes in the construction and in the combination and arrangement of the several parts, provided that such changes 80 fall within the scope of the appended claims. 85

What we claim is:—

1. A musical device, comprising a supporting part having curved ends for engaging the legs of the user when the supporting part is set in the lap of the user, a base connected with the supporting part and a blade member having one end connected with the base. 90

2. A device of the class described comprising a tapered steel strip, a base to which one end of the strip is connected, the other end being held by the hand of the user, supporting members connected with the base and having curved portions for engaging the 95 legs of the user when the device is held in the lap.

In testimony whereof we affix our signatures.

CLARENCE M. FIELDS.
WALTER WORRICK.
